WILLIAM F. REGAN, OF BROOKLYN, NEW YORK, ASSIGNOR, BY MESNE ASSIGNMENTS,
TO EMPIRE PAPER BOTTLE COMPANY, A CORPORATION OF NEW JERSEY.

NECK-FORMING MECHANISM FOR PAPER-BOTTLE MACHINES.

1,222,135.

Specification of Letters Patent. Patented Apr. 10, 1917.

Application filed November 19, 1913. Serial No. 801,823.

To all whom it may concern:

Be it known that I, WILLIAM F. REGAN, a citizen of the United States, residing in the city of New York, borough of Brooklyn, county of Kings, and State of New York, have invented a certain new and useful Neck-Forming Mechanism for Paper-Bottle Machines, of which the following is a specification.

10 In certain prior applications, Serial No. 660,945, filed Jan. 8, 1912 and Serial Nos. 801,824 and 801,825, filed Nov. 19, 1913, to which I am a party, there are disclosed mechanisms for forming the body portions 15 of fibrous containers, such as paper bottles, the latter being characterized by a crimped or plaited tapering portion and a reduced neck portion. This neck portion consists of irregularly positioned or flattened crimps at 20 one end of the tapered part of the bottle, but manifestly said neck portion should be finished in a manner to result in imparting a smooth, cylindrical exterior surface thereto and to bind the crimps or plaits into a firm 25 condition so that the fibrous bottle will not break down at the neck and will properly receive the cap or other closure.

The present invention is a means for forming the neck portion of a bottle, the latter being given a tapering form by the converging crimps. The mechanism embodies a mandrel, means for feeding a strip of adhesive material to the neck portion of an embryo container present on said mandrel, and means for wrapping or coiling the adhesive strip exteriorly upon said neck portion.

30 The feed mechanism is operated to grip and feed the adhesive strip, but at certain intervals said feed mechanism is released from gripping contact with the adhesive strip, whereupon the strip is cut or severed transversely.

40 Means are employed for exerting pressure upon the adhesive strip during the operation of coiling or winding it upon the bottle neck, whereby the strip is wrapped firmly around the crimped neck of the container. Prior to removing the bottle from the mandrel or 45 former, the pressure mechanism and the feed mechanism are operated automatically so as to position them free from contact with the bottle neck and the strip, thus permitting

the bottle to be discharged without interference by the pressure and feed devices. 55

In the accompanying drawings, I have illustrated one practical embodiment of the invention, but the construction shown therein is to be understood as illustrative, only, and not as defining the limits of the invention. 60

Figure 1 is a side elevation illustrating the operative position of the neck band applying device in full lines, the dotted lines showing the parts moved to a position 65 wherein the pressure devices are withdrawn from the path of the forming cylinder and the feed devices are moved away from the path of feed of the neck band strip. 70

Fig. 2 is a side view illustrating the pressure devices in their non-operative positions.

Fig. 3 is a plan view of the devices shown in Fig. 1, the view looking from above the devices positioned above the path of the strip. 75

Fig. 4 is a plan view illustrating the devices below the path of the strip.

A designates a forming mandrel of the kind disclosed in one of the prior applications, Serial No. 801,824, to which I am a party. Said forming mandrel is constructed to produce longitudinal crimps or plaits at the tapering neck portion of the paper bottle. Said mandrel is mounted for rotary 80 and reciprocating movement; and to the mandrel is adapted to be fed an adhesive strip X, whereby the strip is wound or coiled around the compressed or flattened ends of the plaits or folds of the paper 85 bottle, as a result of which the adhesive strip is united to the neck portion of the paper bottle in a manner to retain the plaits or crimps in proper position and to finish the neck of the bottle for the reception of a 90 closure. If desired, a strip of paper of the required width and character may be fed by devices embodying this invention, and during such feed an adhesive may be applied to one surface of the strip; but it is preferred to employ a gummed strip of paper 95 and to moisten the gummed surface of the paper strip as it is fed to the forming mandrel.

100 In the embodiment shown in Fig. 1, the moistening device for the gummed face of

the paper strip embodies a well B within the water of which is immersed a fibrous wick C, the latter being retained in position by a suitable screw c attached to a shoulder 5 portion c' within the well. The upper part of this fibrous wick extends into the chamber of well B above the level of the liquid therein, and this upstanding end of the fibrous wick is in contact with the moistening roller D, the latter being positioned adjacent to the path of feed of strip X so as to contact with the gummed face of said strip. The moistening roller may consist of a suitable fabric or it may consist of a 10 roller covered with fabric, the fabric portion of the moistening roller being in frictional contact with the upstanding end of fibrous wick C, whereby the moisture is supplied to roller D. The roller may be mounted in 15 any desired way within the upper part of the well; as shown said roller is provided with a trunnion d which is journaled in an arm E positioned exteriorly to the tank. This arm is pivoted at e to the lower part 20 of the tank, and said arm E is provided with a tail piece e' having a slot or aperture through which passes a bolt e², the latter retaining a spring E' in coöperative relation to the pivoted arm E, for the purpose of 25 normally pressing the arm in a direction which will position the moistening roller in forcible contact with the gummed face of the adhesive strip.

As shown, moistening roller D is below 30 the path of strip X, and with this moistening roller coöperates a roller D' which is positioned above the path of said strip, whereby the strip X is adapted to pass between the coöperating rollers D D'. Roller 35 D' is carried by a shaft d' which is journaled in a suitable frame (not shown), suitable means being provided for imparting rotary motion to said roller D', so that the roller D' constitutes a driving roller for the 40 pressure mechanism to be presently described.

Mounted loosely on the shaft d' of roller D' is a bellcrank carrying arm F which is adapted to swing on shaft d' as a center, and connected to the free end of this carrying arm F is a curved carrying arm G, said parts F G constituting the two members of a two-part carrying arm for supporting the 45 pressure mechanism in coöperative relation to the bottle forming mandrel A. Member F of the two-part carrying arm is provided with a short upstanding piece f, whereas the curved member G of the two-part carrying arm is likewise provided with a short 50 upstanding member g, said upstanding parts f g being connected by a coiled spring H, the purpose of which is to impart a quick upward movement to arm G at certain stages in the operation of the pressure mechanism.

On the carrying arm F is supported a

shaft i of a pressure roll I, the arm G being loosely fitted on said shaft i to swing thereon as its axis of movement. The free end of curved arm G supports a shaft j of another pressure roll J, whereby pressure roll J is mounted directly on curved arm G so as to be movable therewith into and out of operative relation to mandrel A. Pressure rolls I J in the operative position of the pressure mechanism coöperate with the forming mandrel A at diametrically opposite points, that is to say pressure roll I is above the mandrel, whereas pressure roll J is below the mandrel, see Fig. 1, but when the mandrel A is to be moved endwise then 70 the parts operate to raise roll J above the mandrel and to lift roll I away from the mandrel, all as indicated in Fig. 2.

In connection with the pressure rolls I J it is preferred to employ a flexible pressure 75 member herein shown as an endless band K, the latter passing around rolls I J and being shiftable therewith into and out of operative relation to mandrel A, said flexible band K being adapted to conform to the curvature of mandrel A and to fit part way around said mandrel for the purpose of exerting pressure upon that part of the neck forming strip X intermediate said pressure rolls I J. For the purpose of retaining the flexible pressure band K in a taut condition during the 80 operation of moving the pressure mechanism toward and from the forming mandrel a tension roller L is employed. This tension roller is supported by a shaft l on a bellcrank L', the latter being pivoted at m to curved arm G intermediate the arms of the latter. To the bellcrank L' is connected a coiled spring M adapted to exert its tension 85 on said bellcrank L' for the purpose of retaining the endless band in a taut condition. The roller which is carried by said bellcrank L' is positioned for frictional engagement 90 with endless band K intermediate the pressure rolls I J, and the spring M by which tension is applied to said tension roller is connected at one end to short upstanding member g of pivoted arm G.

Motion is imparted to roll I from roller D' by a train of gears n o p. The gear n 95 is secured rigidly to the shaft of roller D'; gear p is secured rigidly to the shaft of pressure roll I, whereas gear o is an idler loosely mounted on a pin o' attached to carrying arm F, whereby the motion of roller D' is communicated through gear n to the idler o which in turn drives gear p and the pressure roll I, the latter operating to impart motion to endless pressure band K, which pressure band is kept normally in a 100 taut condition by the action of roller L which is under the tension of spring M.

Means are provided for automatically operating the two-part jointed arm F G in order to position the pressure mechanism 105

into and out of operative relation to the forming mandrel. The upstanding member f of arm F is provided with a stud O which projects into a longitudinal slot g which is formed in a link Q. Said link extends above arm F and its other end is connected loosely to a pin p' which is provided on the upstanding member g of arm G. To the pin p' is attached one end of a bent operating rod P, the other end of which rod is pivoted by a pin p^2 , to a bell crank P'. The other end of the bell crank is pivoted by a pin q' to a driving rod Q', the lower end of which is provided with a roller q^2 positioned to ride in a groove r of a cam R mounted on a shaft R' whereby the operation of the cam imparts motion to rods P Q and bell crank P', for the purpose of first lifting arm G and thereafter turning arm F on the pivot d' for the purpose of moving the pressure mechanism into the non-operative position of Fig. 2 or into the operative position shown in full lines in Fig. 1.

Strip X is in a roll α and it is moved or advanced periodically by the operation of a plurality of pairs of feed rolls S S', T T'. The rolls S T are positioned above the path of feed of the strip; they are supported by shafts on suitable bearings of the frame work (not shown) and motion is given thereto by any suitable or appropriate means. The lower rolls S' T' are mounted for movement relative to the upper rolls S T and these lower rolls have frictional contact with the paper strip and with the upper rolls so that the lower rolls will co-operate with the driven upper rolls for the purpose of feeding the strip when said lower rolls occupy the operative position shown in full lines in Fig. 1. Roll S' is loosely journaled on an arm s of a bell crank S ^{2} , and to one arm of this bell crank is pivoted a link t , the other end of which is pivoted to a lever T ^{2} , said lever T ^{2} having the feed roll T' loosely mounted thereon. The bell crank S ^{2} and lever T ^{2} support the lower rolls S' T' normally in frictional contact with the paper strip, but said rolls S' T' are simultaneously withdrawn from the path of the strip by moving them into the dotted line position of Fig. 1, said movement being effected by a cam U having a groove u in which operates a roller u' on one end of a link U', the other end of which is pivoted by a pin u^2 to bell crank S ^{2} . It is manifest that cam U operates to move the lower feed rolls S' T' into co-operative relation to the upper feed rolls S T so that the two sets of feed rolls will frictionally engage with the strip X for the purpose of imparting movement to the strip, but when a predetermined length of strip shall have been fed in the forming mandrel, cam U will then operate to withdraw the lower feed rolls

S' T' to the dotted line position of Fig. 1 in order to release the grip of the feed rolls on the strip, thereby arresting the feed of said strip.

Means are provided for cutting the strip periodically, and in Fig. 1 there is shown one form of cutting mechanism consisting of the shears V V' positioned between the feed rolls and adjacent to the path of feed of the strip. These shears are operated at the required time to sever the paper strip when a predetermined length of said strip shall have been advanced by the feed rolls to the wrapping devices by which the strip is coiled around the neck portion of the paper bottle.

With the parts in the position shown by full lines in Fig. 1, the feed rolls engage with the paper strip, rollers D D' are in contact with said strip so as to supply moisture to the gummed face thereof, rolls I J and pressure band K are in co-operative relation to mandrel A. As the mandrel is rotated the moistened gummed strip is wrapped or coiled around the crimps or plaits at one end of the paper bottle, and simultaneously with the wrapping or coiling operation rolls I J and band K exert pressure upon the strip for the purpose of wrapping it tightly around the plaited or crimped part of the bottle neck. When a predetermined length of the strip is wrapped around the bottle neck shears V V' sever the strip, cam U operates to withdraw the feed rolls S' T' from co-operative relation to feed rolls S T, respectively, and cam R operates rod P to shift the pressure mechanism away from its operative position relative to the mandrel. When the rod P is moved toward the right in Fig. 1, it pulls on the pin p' and thus acts on member g of arm G so as to swing said arm G on shaft i as a center, thus lifting the arm G to the dotted line position of Fig. 1, whereby the arm G, pressure roll J and band K are withdrawn from the forming mandrel, and during this movement bell crank L' moves upwardly with arm G, whereby the spring M is effective in keeping the tension roller L in engagement with the pressure band so that the latter is retained in a taut condition. The upward movement of arm G under the pull of rod P imparts sliding movement to link Q, the slotted part of which moves freely over the stud O on the member f of arm F, at which time spring H co-operates with arm G for quickly lifting it to the raised position, and when the end wall of the slot g impinges said stud O, the rod P thus exerts a pull through the link Q on the stud O, as a result of which the arm F is lifted on the axis afforded by shaft d' , whereby the pressure roll I is lifted away from the mandrel A, the entire pressure mechanism being thus quickly withdrawn from operative relation to the mandrel.

Manifestly, the mandrel may now move endwise to a position for discharging the paper bottle, or for the performance of any other work thereon. When the mandrel resumes its operative relation to the winding mechanism for applying the strip to the neck of the next bottle the rod P is operated to lower the arms G I for the purpose of restoring pressure rolls I J and pressure band K into coöperative relation to the mandrel, and the feed rolls having been restored to gripping engagement with the paper strip, said strip is fed forward over and in contact with the moistening roll and below the rollers D' I so that the strip will be directed to and around the neck portion of the paper bottle on the mandrel, the devices operating to exert pressure upon the paper strip simultaneously with the operation of winding said paper strip around the neck of the paper bottle.

Having thus fully described the invention, what I claim as new, and desire to secure by Letters Patent is:

25 1. In a paper container machine, the combination with a mandrel upon which is adapted to be formed a container with a crimped mouth portion, of feed means for directing to the crimped material of said mouth portion a separate strip of material the width of which is equal substantially to the crimped mouth portion of the container whereby the separate strip is adapted to be wound externally upon the crimped mouth portion of the 30 container, and pressure mechanism including coöoperating rolls and a band positioned in the path of feed of said separate strip, said pressure mechanism coöperating with said mandrel for applying pressure to the separate strip and to the crimped material of the container mouth during the winding of the separate strip thereon.

2. In a paper container machine, the combination with a mandrel upon which is adapted to be formed a container with a crimped mouth portion, of feed means for directing to the crimped material of said mouth portion a separate strip of material the width of which is equal substantially to the crimped mouth portion of the container whereby the separate strip is adapted to be wound externally upon the crimped mouth portion of the container, coöperating pressure rolls and an endless band positioned to 50 partially envelop that part of said mandrel adapted to contain the crimped mouth of the container, said rolls and band operating to apply pressure to the crimped material and to the separate strip while winding the latter upon the crimped material, and means for bodily shifting the pressure rolls and band relatively to the path of feed of the separate strip.

3. In a paper container machine, the combination with a mandrel upon which is

adapted to be formed a container with a crimped mouth portion, of an intermittently-operated feed mechanism for directing to the crimped material of the container mouth a definite length of narrow material the width of which is equal at least to the crimped material of the container mouth, whereby the narrow material is adapted to be wound externally upon the crimped material present upon the mandrel, pressure mechanism partially enveloping that part of the mandrel to which the narrow strip is directed, and means for shifting said pressure mechanism relatively to the mandrel whereby the pressure mechanism is adapted to be withdrawn from contact with the coiled strip and the container on the mandrel is free from the pressure exerted by said pressure mechanism.

4. In a device of the class described, the combination with a container-forming mandrel, of strip feeding rolls, pressure rolls, a flexible band in coöperative relation to the mandrel and the pressure rolls for wrapping a strip upon a crimped neck of the container and for exerting pressure upon said crimped neck and the strip, and automatic mechanism for shifting the strip feeding rolls, the pressure rolls and the flexible band relative to the path of the strip.

5. In a device of the class described, the combination with a mandrel, of strip feeding rolls for feeding a strip into position to be coiled upon the crimped neck of material wound on the mandrel, coöperating rolls and a flexible band positioned relatively to the mandrel for compacting the crimped material and for exerting pressure upon a strip to be wrapped around said crimped material, and means for simultaneously shifting said strip-feeding rolls and the coöperating rolls and band relative to the path of the strip.

6. In a device of the class described, the combination with a forming mandrel adapted to produce a container with a crimped neck portion, of strip-feeding rolls, means for shifting said strip-feeding rolls relative to the path of feed of a strip, pressure rolls and a flexible band coöperating with said forming mandrel for compacting the crimped material on the mandrel and for exerting pressure on the strip while wrapping the latter on said crimped material, and automatic means for shifting said strip feeding rolls and simultaneously therewith moving the pressure rolls and the flexible band out of operative relation to said forming mandrel.

7. In a paper container machine, the combination with a single mandrel having a part unitary therewith upon which is adapted to be formed a container with a crimped mouth portion, of feed means for directing to said definite part unitary with the man-

5 drel a separate strip of material the width of which is equal at least to the crimped mouth portion of the container whereby the separate strip is adapted to be wound externally upon said crimped mouth portion of the container, a plurality of coöperating pressure devices adapted when in operative position to partially envelop that definite part of the mandrel upon which the separate 10 strip is to be wound, and means for shifting said pressure devices simultaneously with respect to said mandrel, said shifting means being effective in imparting movement to the pressure devices to such an extent as to free the same from contact with the mandrel and to afford the clearance requisite for the withdrawal with the mandrel of the formed 15 container from the pressure devices.

8. In a paper container machine, the combination with a mandrel upon which is adapted to be wound and crimped a web of material to form a container with a crimped mouth portion, of feed means operable to direct to a definite part of said mandrel a 20 separate strip of material the width of which is equal at least to the crimped mouth of said container, an endless pressure member positioned to partially envelop the definite part of said mandrel upon which the 25 separate strip is to be wound, and means for shifting said pressure strip relatively to the mandrel.

9. In a paper container machine, the combination with a mandrel upon which is adapted to be wound and crimped a web of material to form a container with a crimped mouth portion, of feed means operable to direct to a definite part of said mandrel a 30 separate strip of material the width of which is equal at least to the crimped mouth of said container, coöperating rolls and an endless band positioned to partially envelop said definite portion of the mandrel upon which the separate strip is adapted to be 35 wound, and means for shifting the rolls and the band simultaneously with respect to said mandrel.

10. In a device of the class described, the combination with a mandrel upon which a 40 web of material is adapted to be wound, of feed rolls and a flexible band for feeding an adhesive strip into a position to be coiled upon the neck portion of a container positioned upon said mandrel, a moistener receptacle embodying a roller to which tension is applied by a spring-actuated arm, and pressure rolls coöperating with said 45 flexible band for exerting pressure upon the strip simultaneously with its application to the container.

11. In a paper container machine, the combination with a mandrel upon which is adapted to be wound and crimped a web of material to form a container with a crimped 50 mouth portion, of feed means operable to

direct to a definite part of said mandrel a separate strip of material the width of which is equal at least to the crimped mouth of said container, a jointed member positioned in such relation to said definite part of the mandrel as to extend partially around the same, a plurality of pressure devices movable with said jointed member, and means for operating the jointed member whereby the pressure devices are positioned to co-operate with the mandrel during the application of the separate strip to the crimped material and to be withdrawn from contact with said crimped material and the narrow strip wound thereon.

12. In a device of the class described, the combination with a mandrel, of strip feeding means, a pivoted arm having another arm pivoted thereto, a spring connecting the two arms, pressure mechanism carried by said arms in position for exerting pressure upon the material wound on said mandrel, and means for imparting movement to said pivoted arms for shifting the pressure mechanism with respect to said mandrel.

13. In a paper container machine, the combination with a mandrel upon which is adapted to be wound and crimped a web of material to form a container with a crimped mouth portion, of feed means operable to direct to a definite part of said mandrel a separate strip of material the width of which is equal at least to the crimped mouth of said container, a member composed of separate parts pivoted and spring controlled for conjoint action under one condition and for independent action under other conditions, a plurality of pressure devices carried by said parts composing the member, and means for imparting movement to the member so as to position the pressure devices in operative relation to the mandrel and to quickly withdraw said pressure devices from contact with said mandrel.

14. In a device of the class described, the combination with a mandrel, of strip feeding means, a jointed arm adapted to be shifted into and out of operative relation to the mandrel, pressure rolls carried by said arm, an endless pressure band supported by the arm, a tension device coöperating with said pressure band and supported by the arm, and means for imparting movement to the arm.

15. In a device of the class described, the combination with a mandrel, of strip feeding means, a jointed arm positioned to extend into coöperative relation to the mandrel, a spring connecting the members of said arm, a slotted link pivoted to one member of the arm, a stud fixed on the other member of said arm and fitted in the slot of said link, an operating rod connected to one member of the arm, and pressure mechanism carried by the arm.

16. In a device of the class described, the combination with a mandrel upon which a web of material is adapted to be wound, of sets of feed rolls for advancing a strip to 5 a marginal portion of the material wound upon said mandrel, operating means whereby the relative positions of said feed rolls may be shifted, pressure mechanism in cooperative relation to the mandrel for applying pressure to the strip while wrapping it 10 upon the material coiled on the mandrel,

and separate operating means for shifting the pressure mechanism into and out of operative relation to the mandrel.

In testimony whereof I have signed my ¹⁵ name to this specification in the presence of two subscribing witnesses.

WILLIAM F. REGAN.
